PASSENGER LOADING BRIDGE FOR AIRPORTS

Perry N. Fisher, Huntsville, Ala., assignor to Brown Engineering Company, Inc., a corporation of Alabama

Filed July 22, 1969, Ser. No. 18,290

Term of patent 14 years

Int. Cl. D25—05

U.S. Cl. D13—1

FIG. 1 is a perspective view of a passenger loading bridge for airports embodying my new design;

FIG. 2 is a right side elevational view thereof;

FIG. 3 is a top view thereof;

FIG. 4 is a left side elevational view thereof; and

FIG. 5 is an elevational view of the outer end of the passenger loading bridge for airports embodying my design. The inner end thereof lies against a wall of an airport terminal building and therefore possesses no ornamental characteristics.

The fragmentary showing in dotted lines of a building in the several views is for illustrative purposes only.

I claim:

The ornamental design for a passenger loading bridge for airports, substantially as shown and described.
